UNITED STATES PATENT OFFICE.

JOSÉ A. VILLAVICENCIO, OF CARACAS, VENEZUELA.

APPARATUS FOR HULLING COFFEE, RICE, &c.

SPECIFICATION forming part of Letters Patent No. 309,112, dated December 9, 1884.

Application filed September 25, 1884. (No model.) Patented in Venezuela August 20, 1884, No. 1, Issue No. 21.

To all whom it may concern:

Be it known that I, JOSÉ A. VILLAVICENCIO, of Caracas, in the Republic of Venezuela, have invented a new and useful Improvement in 5 Apparatus for Hulling Coffee, Rice, Corn, and other Grains, of which the following is a specification.

My invention relates to that class of apparatus for hulling coffee, rice, and other grain 10 in which the grain is subjected to the combined action of aqueous vapor or steam and attrition or rubbing.

My invention consists in novel combinations of parts, hereinafter described, and pointed 15 out in the claims, whereby the coffee, rice, or other grain may be subjected to a vigorous rubbing action after or while being moistened with aqueous vapor or steam.

In the accompanying drawings, Figure 1 is 20 a vertical transverse section of an apparatus embodying my invention. Fig. 2 is a vertical longitudinal section thereof. Fig. 3 is a transverse section of the cylindrical casing alone, and on the plane of the dotted line $x-x$, Fig. 25 2; and Figs. 4 and 5 are sectional views, similar to Figs. 1 and 2, and illustrating a modification of my invention.

Similar letters of reference designate corresponding parts in all the figures.

Referring first to Figs. 1, 2, and 3, A designates a cylinder or cylindric casing, which may be composed of sheet or plate metal, and of any suitable size. The cylinder or casing is supported in any suitable manner in a horizontal or nearly horizontal position upon a 30 stationary frame, which may be of wood or metal, and of any suitable construction. As here shown, the frame consists of end pieces or standards, B, and longitudinal rods or stretchers B', connecting them, and the ends of the cylinder are furnished with knees or brackets a , which rest upon said end pieces or standards, and so support the cylinder. In this example of the invention the cylinder A is composed of two semi-cylindric sections, each of which comprises semicircular portions of the heads, and these sections are secured together by bolts b , inserted through ears or lugs, with which they are provided. The purpose of this construction will be explained hereinafter.

Through the cylinder A extends a concentric shaft, C, which is supported and capable of rotation in bearings c on the end frames, B, and upon this shaft is a pulley, d, whereby it 55 may be rotated by a driving-belt. The shaft may be turned by a hand-crank, if desired.

Upon the shaft C, at intervals in its length, are wheels C', which are of light construction, and are slightly smaller than the internal diameter of the cylinder A, so that they will 60 rotate therein freely with the shaft. These wheels C' consist of hubs e , whereby they are secured on the shaft, spokes e' , and rims e'' , all of which are of light construction, and may 65 be of wrought or cast metal.

Between the wheels C' are skeleton frames or wheel-like partitions A* in the cylinder A, which are non-rotary. As here shown, each frame or skeleton partition A* consists of a 70 hub or center, f, which is large enough to receive the shaft C through it, spokes or radial arms f' , and a rim, f'' , which is secured in fixed position to the interior of the cylinder.

In order to enable the shaft C and its wheels 75 C' to be placed in position, the wheel-like skeleton partitions or frames A* are divided or composed each of two semicircular sections or portions secured in the two sections of which the cylinder is formed. The line of division 80 is through the hubs or centers f , as shown best in Fig. 3, and the upper halves of the several wheel-like frames A* are secured in one half of the cylinder, while the other halves thereof are secured in the other half of the 85 cylinder. The upper half of the cylinder, with its contained halves of the several wheel-like frames, is removed. The shaft and wheels C C' are then laid in the lower half of the cylinder, and the upper half of the cylinder is 90 then placed in position and secured by its bolt b . The shaft and wheels C C' constitute a rotary reel or stirrer.

At the top of the cylinder A is a feeding-hopper, D, which is of large capacity, and is 95 provided with a sliding gate or door, g, whereby its communication with the cylinder is controlled. At the bottom the cylinder is provided with a hinged door or cover, E, which, as shown, extends the full length of the cylinder. 100

The cylinder A is provided with an inlet-

pipe, *h*, controlled by a valve, *h'*, and through this aqueous vapor or steam may be introduced into the cylinder.

In the operation of my machine the coffee, 5 rice, corn, or other grain is first placed in the hopper *D*, and the stirrer or reel being rotated, the sliding door or gate *g* is opened, and the contents of the hopper are allowed to pass into the cylinder. Steam is admitted through 10 the pipe *h*, and serves to soften or render moist the grain, and the rotary reel or stirrer, acting in conjunction with the fixed wheel-like frames *A**, produces friction or attrition between the particles of grain, and the hulls are 15 thereby separated or removed.

When the operation has been continued for a sufficient time, the door or cover *E* is opened, and the entire contents of the cylinder discharged, after which the grain is passed 20 through a winnowing-machine or separator to separate the hulls from the solid grain.

The spokes or arms *e* of the wheels *C* and the arms *f* of the fixed wheel-like frames *A** may be either straight, as here shown, or 25 curved like the arms of a pulley.

In the modification of my invention shown in Figs. 4 and 5 the cylinder *A* is shown as undivided, and is supported by knees or brackets *a* on the end pieces or standards, *B*, of a frame, which also comprises longitudinal rods 30 or stretchers *B'*. This cylinder *A* is provided with a feeding-hopper, *D*, and sliding gate or door *g*, and at the bottom of the cylinder is a door or cover, *E*, which controls the delivery- 35 outlet of the cylinder.

Concentric within the cylinder is a shaft, *C*, which is supported in bearings or boxes *e*, and on which is a driving-pulley, *d*. This shaft carries a number of wheels, *C'*, severally composed of a hub, *e*, spokes or arms *e'*, and a 40 rim, *e''*, as before described, and these wheels are connected by numerous rods or small bars, *i*, which pass through the rims of the several

wheels and through the spokes or arms at different distances from the center. In this example of my invention the shaft *C*, with the wheels *C'* and the rods or bars *i* connecting them constitute a rotary reel, whereby friction or attrition among the grains is produced. In this case, also, the cylinder or casing *A* is supplied with aqueous vapor or steam through a pipe, *h*, and under control of a valve, *h'*. 45 50

What I claim as my invention, and desire to secure by Letters Patent, is—

1. In an apparatus for hulling coffee, rice, 55 corn, and other grain, the combination, with a cylindric casing or shell, of a rotary reel or stirrer arranged therein, consisting of a shaft and a number of separate wheels or skeleton frames, each composed of a hub, spokes, or 60 arms, and a rim, and secured on said shaft at intervals in its length, and a pipe for introducing aqueous vapor or steam to moisten or soften the hulls, substantially as herein described. 65

2. In an apparatus for hulling coffee, rice, corn, and other grain, the combination, with a cylindric casing or shell, of a reel or stirrer consisting of a rotary shaft and a number of separate wheels or skeleton frames, each composed of a hub, arms, and a rim, and secured upon the shaft at intervals in its length, and wheel-like frames fixed in the casing or shell between the said wheels and in planes transverse to the axis of the cylinder and shaft, substantially as herein described. 70 75

3. The combination, with divided cylindric casing or shell *A* and the divided wheel-like frame *A**, secured therein, of the rotary shaft *C*, having wheels or skeleton frames *C'*, secured upon it between the said fixed frames, substantially as herein described. 80

JOSÉ A. VILLAVICENCIO.
